their attorney

UNITED STATES PATENT OFFICE.

WILLIAM ERNEST CLIFTON AND JOHN STURTON EWART, OF NOTTINGHAM, ENGLAND,
ASSIGNORS TO THE CLIFTON-EWART CONSTRUCTION COMPANY LIMITED, OF NOTTINGHAM, ENGLAND.

CONSTRUCTION OF CONCRETE ROOFS.

Application filed June 27, 1921. Serial No. 480,844.

(GRANTED UNDER THE PROVISIONS OF THE ACT OF MARCH 3, 1921, 41 STAT. L., 1313.)

To all whom it may concern:

Be it known that we, WILLIAM ERNEST CLIFTON and JOHN STURTON EWART, subjects of the King of England, both residing in Nottingham, England, have invented certain new and useful Improvements in the Construction of Concrete Roofs (for which we have filed an application in Great Britain September 24, 1919, Patent No. 155,385), of which the following is a specification.

This invention relates to improvements in the construction of concrete floors and roofs, and its object is to provide a construction which is both strong and weather resisting, while the sectional shape of the members comprising the same is such that they can be readily and economically produced.

According to the present invention, a roof is built up of a series of reinforced concrete girder members which are all of the same angle shape in cross section, and are placed side by side close together so as to form a complete roofing, each member being long enough to extend from one principal to an adjacent principal and to be supported thereby, whereby the use of rafters between the principals is obviated.

A perspective view of a roof construction according to the invention is illustrated in the accompanying drawing.

In the roof construction shown in the drawing the angle section members A of reinforced concrete are all laid in an inverted position, parallel to the ridge of the roof, the angle C of each is on the upper side, and the lower edge of the upper web of each overlaps the angle C of one below it. At the ridge, the space between the two upper members A is closed in by means of a cap G. All the members A are of the same L-section and each is supported by two principals of inverted V-shape, one at each end of the members A.

What we claim as our invention and desire to secure by Letters Patent is:—

1. In a roof, the combination of two prin-

cipals spaced apart, and a plurality of longitudinal reinforced concrete members all of the same L-section arranged in a row each parallel to the roof ridge with their angles uppermost, each member having one limb which is spaced away from the corresponding limb of the adjacent members and is supported by its free edge at its two ends only on said principals, and each member except an end one in the row having its other limb overlapping the angle of the member below it, and the length of each member measured in the direction in which it extends between the principals being great in relation to its measurement at right angles thereto.

2. A roof, comprising in combination two principals of inverted V-shape, and two sets of longitudinal reinforced concrete members all of the same L-section, the members in each set being arranged in a row parallel with the roof ridge and parallel one with another with their angles directed upwards, one set on each slanting side of the principals, each member in one set having one limb spaced away from the corresponding limb of the adjacent members and supported by its free edge at its two ends only by said principals, and each member in each set except an end one in the row having its other limb overlapping the angle of the member below it in the same set, and an inverted V-shaped longitudinal reinforced concrete member arranged parallel with said members of L-section and having its limbs resting respectively upon the upper end members of the two rows of members.

In testimony whereof we have signed our names to this specification in the presence of two subscribing witnesses.

WILLIAM ERNEST CLIFTON.
JOHN STURTON EWART.
